UNITED STATES PATENT OFFICE.

CLYDE E. COCHRAN, OF CLEVELAND, OHIO.

INDUSTRIAL TRUCK.

Application filed October 4, 1920. Serial No. 414,537.

To all whom it may concern:

Be it known that I, CLYDE E. COCHRAN, residing at Cleveland, in the county of Cuyahoga and State of Ohio, have invented 5 a certain new and useful Improvement in Industrial Trucks, of which the following is a full, clear, and exact description, reference being had to the accompanying drawings.

10 This invention relates to portable cranes adapted to be electrically operated and mounted on self-propelled trucks, and an object of the invention is to arrange the usual battery box in such fashion that it, 15 together with the winding mechanism and its motor, counterbalances partially or entirely the crane boom and load carried thereby in any position of the crane.

A feature of my invention is such arrangement of the crane and the battery box with reference to the loading platform and the front frame housing the propelling motor that the loading space will not be unduly reduced and such that the battery 15 box will normally stand in a position within the wheel base of the truck and thus is without interference with the loading capacity of the truck.

Another specific object of the invention is 20 to so arrange the crane that the boom may be raised and effectively latched by the continued action of the lifting cable, enabling the load to be swung over the platform and deposited thereon, the lowering of the load 25 onto the platform being accomplished while the boom is latched in its raised position.

In arranging the crane to embody these characteristics I prefer to employ a telescoping member in tension which connects the boom with the support therefor, and I so connect these elements with a latch that the raising of the crane causes an automatic operation whereby it is latched in its high 45 position, but may be manually released to lower the boom. The telescoping tension member forms a tie between the rotatable frame and the upper portion of the boom whereby sufficient strength to support a comparatively heavy load may be accomplished 50 by a comparatively light construction.

The above and other features will be hereinafter more fully set forth in the following description which relates to the drawings and the essential characteristics will be set forth in the claims.

In the drawings Fig. 1 is a plan of a

portable truck having a crane and embodying the features of my invention; Fig. 2 is a plan of the device shown in Fig. 1; Fig. 3 is a section through the adjustable 60 tie rod; Fig. 4 is an end view of a truck having the crane swung over the side thereof.

The general arrangement of the mechanism embodying the features of my invention comprise a crane having a boom 10 supported by and rotatably mounted on a pillar 17 on the platform 11 of a wheel truck, which has a propelling electric motor. Hoisting mechanism, preferably independent of the truck propelling mechanism, comprises a motor 12, winding drum 13, cable 14 and fall 15. The hoisting mechanism is mounted above the battery, which is carried in a crate or box-like structure 16, and both 75 are rotatably supported on the pillar 17 on the opposite side from the boom. The weight of the winding mechanism and battery are thus adapted to more or less nearly counterbalance the weight of the boom and 80 the load.

Referring to Fig. 1, the base or bearing block 20, which supports the weight of the hoisting mechanism, comprises a casting having a hollow tubular passageway adapted 85 to receive the post 17 and having the flanges 21, 22, to secure it to the platform 11 and front housing 23 of the truck frame. This bearing block is rigidly secured to the platform, preferably in the longitudinal mid 90 line thereof to enable the crane to be swung an equal distance at either side of the platform. The post 17, extends vertically from the bearing block 20, and forms a journal for the boom and the mechanism that swings 95 therewith. At the base of these swinging posts is a collar 24 which is adapted to bear against a thrust bearing 25 at the top of the block 20. An upper guide bearing, not shown, is positioned near the top of the 100 shaft and is used not only to guide but to take up the side thrust resulting from the difference in weight and leverage between the hoisting mechanism and load.

Positioned above the collar 24 on the post 105 17 and rigidly secured to the collar is a bracket 26 which has projecting ears 29 having apertures 28 thereon through which a pin 29 is passed to pivotally secure the base of the boom 10. The boom pivot bracket 110 26 has rearwardly projecting members 30 to serve as supports for the battery housing

16 and as means for rigidly securing the bracket thereto. The batteries placed in the casing 26 serve to furnish power for the truck driving motor as well as to furnish power for the motor which elevates the load.

The boom 10 pivotally mounted at 29 to the boom pivot bracket 26 extends outwardly and upwardly and carries at the 10 hoisting end a sheave 31 and the guard block 32. The lower portion of the guard block 32 is adapted to be engaged by an abutment 19 on the fall 15 to enable a continued pull on the cable 14 to raise the 15 boom to some elevated position, at which it may be locked by mechanism hereafter described. The boom may be made of any structural material, such as channel or angle bars pressed to the desired form, and preferably 20 comprises two such members spaced apart at the point of pivoted connection and converging so that a sheave may be readily confined between them at the hoisting end.

25 The hoisting drum 13 together with the motor and the battery 35 (which furnishes current for both the raising motor and the propelling motor) is positioned on the housing 16 and supported by the standards 35, 36, which carry the upper guide bearing on the post 17. The lower portion of the housing 16 is adapted to clear that portion 37 of the truck frame which is above the propelling motor. Since the battery housing 35 is adapted to rotate whenever the boom is rotated about the post 17 the rear portion 38 of the housing 16 is arcuate in form. The housing is preferably a skeleton structure built of steel bars as 40 and 41.

40 A handle 42 may be rigidly secured to the housing to enable the boom to be manually rotated, and a retaining lever 43 operated by the handle 44 may serve to lock the crane to the standard 39 at any desired position. 45 Suitable notches in the arcuate portion 38 of the housing may be employed to secure the crane in any desired position.

As heretofore stated, the hoisting drum 13 may be used to raise the boom when the 50 fall 15 engages the guide block 32. To secure the boom in any desired position, however, I provide a telescoping tie rod comprising interengaging members, one of which is connected to the boom and the 55 other to the frame. As shown in Fig. 3 my interengaging device comprises a toothed rod 45, the outer end of which is formed into a fork 34 pivotally connected to the boom by the same pivot pin 33 on which the 60 sheave 31 is mounted, the other end of this rod being slidably mounted in the tubular portion 46, of the guide bar 47. The teeth on the bar 45 are of ratchet form having their engaging surfaces undercut to prevent 65 the pawl 48, supported by the bar 46 and

adapted to engage the teeth from below, from dropping out when the tie rod is substantially horizontal. As shown in Fig. 2, the guide bar 47 is pivotally mounted by a pin 49 to the bracket 50 rigidly secured to the frame. A space is provided between the arms of the guide bar 47 to permit the rod 45 to move inwardly as the boom is raised.

When the boom is being raised the bar 45 will move inwardly, its teeth passing over the pawl 48, which springs into the successive notches. When the desired height is reached the pawl is automatically seated in the adjacent notch and held therein by the action of the spring 51. This spring bears 80 against an abutment 52 and shoves a rod 55 forwardly which, through the rocker 53 and link 54, urges the pawl 48 upwardly.

To lower the boom the fall 15 is brought into engagement with the block 32 and a slight tension exerted thereon to relieve the pressure of the engaging tooth of the rod 45 against the pawl 48. A handle 56 on the rod 55 is provided for the operator to manually pull the rod and thus disengage 90 the pawl 48. When the boom is lowered to the desired height the operator may release the handle whereupon the spring will again urge the pawl into engagement with the adjacent tooth of the bar 45, thereby bringing 95 the boom to a stop.

In operation, the rotary motion of the boom is obtained when the operator disengages the latch 43 and urges the crane about the post 17 by means of a manual force 100 exerted on the handle 42. As the boom is swung to the right or left of the platform the hoisting mechanism together with the battery is swung to the left or right and is always opposite and counterbalances the 105 boom with its average load. Assuming that the boom is in a position shown in full line in Fig. 4, then to lower the boom the fall 15 is brought into engagement with the guide block and a slight tension is put on 110 the hoisting cable, thereby relieving the pressure of the ratchet bar 45 against the retaining pawl 48. The operator then pulls the handle 56 against the tension of the spring 51, thereby releasing the pawl. The 115 handle is held manually in this position and the winding cable is paid out, whereupon the weight of the boom will cause it to move downwardly while the fall 15 is held against the block 32. When the desired position is 120 attained the operator releases the handle 56, and the pawl engaging the adjacent tooth holds the boom, and a further paying out of the hoisting cable permits the fall 15 to leave the block 32 and to drop, due to 125 its own weight.

From the foregoing description it will be seen that I have provided a hoisting mechanism which may be readily adapted for mounting on a portable truck with very 130

little reduction of the loading space thereon and will be effectively counterbalanced by the battery and raising mechanism to maintain stability in any position in the boom; also that I have provided an adjustable tie rod which is adapted to be secured to the boom at the point where the load is supported thereon, thus furnishing by a comparatively light construction, the requisite strength to effectively withstand the strain. The mechanism is compact, efficient and capable of being cheaply manufactured.

Having thus described my invention, I claim:

1. The combination with a wheel truck having a front frame housing for the truck propelling mechanism and a horizontal load supporting platform extending rearwardly from said housing, of a bracket mounted on the platform and abutting the rear of the housing, a vertical post carried by the bracket, a member swiveled on the post, a thrust bearing between said member and the bracket, a boom pivoted to said member near its lower end, and a frame for a battery box extending from the members in the opposite direction to the boom.
2. In a crane, the combination with a support, of a boom pivotally mounted thereon, a hoisting rope leading over the boom, hoisting mechanism carried by the support, means for mounting the support whereby the boom and mechanism may be simultaneously rotated, telescopic tie rods for retaining the boom in an elevated position, said rods comprising inter-engaging members, one member thereof being connected to the support, the other member being connected to the boom, and means for manually releasing the inter-engaging member.
3. In a crane, the combination with a rotatable support, of a boom pivotally mounted thereon, inter-engaging members extending between the support and the boom and pivotally connected to them and comprising a ratchet bar, a telescoping member therefor, and means for holding the ratchet bar in various positions in the tubular member.
4. In a crane, the combination with a support, of a boom pivotally mounted thereon, means for moving the boom about the pivot, inter-engaging members between the support and the boom, comprising one member pivotally mounted on the support and another member pivotally mounted at the free end of the boom, one of said members having ratchet teeth, a pawl adapted to engage the toothed member, and means for operating the pawl to release the toothed member, said means being operable independently of the means for moving the boom.
5. The combination with a wheel truck having a front frame housing for the truck propelling mechanism and a horizontal load supporting platform extending rearwardly from said housing, of a post rising from the platform adjacent the rear of the housing, a member swiveled on the post, a thrust bearing supporting said member, a boom pivoted to said member near its lower end, a frame for a battery box extending from the member in the opposite direction to the boom, a winding mechanism and motor supported above the battery box and movable therewith, a cable leading from the winding mechanism over the boom, and an adjustable tie connection between the upper portion of the boom and the member supporting the winding mechanism.
6. In a crane, the combination with a rotatable support of a boom pivotally mounted adjacent the lower extremity of the support, a platform carried by the support and extending in a direction opposite to the boom, a battery housing mounted on the platform, a motor operated winding mechanism mounted upon the battery housing, a flexible member extending from the winding mechanism over the end of the boom and boom adjusting means connected to the outer end of the boom at one end and to the support adjacent the winding mechanism at the other end and manually operated means for releasing said last named means, whereby the boom may be lowered by a paying out movement of said winding mechanism.
7. In a crane, the combination with a rotatable support of a boom pivotally mounted thereon, a platform rigid with the support, a battery housing mounted on the platform, a pivot member upon which the boom support revolves, said pivot member extending substantially the height of the battery housing, a second platform on the boom support disposed above the battery housing, a winding mechanism mounted thereon, a flexible member extending from the winding mechanism over the opposite end of the boom and boom positioning means comprising a pair of members pivotally connected to the boom and said boom support, and latching means therebetween for locking the boom in various elevated positions.
8. The combination with a wheel truck having a front frame housing for the truck propelling mechanism and a horizontal load supporting platform extending rearwardly from said housing, of a vertically extending member secured to said platform, a rotatable support mounted on said member, a boom pivotally mounted on the support adjacent its lower extremity, a platform on said rotatable member, a battery housing mounted on said platform, a winding mechanism mounted on said rotatable member above the battery housing, an upright frame member rigid with the truck frame and extending adjacent the battery housing, means for

locking the boom in an adjusted position, thereon for engaging said boom support and means on said upright member for engaging the boom support whereby rotation of said boom supporting member may be prevented.

9. The combination with a wheel truck having a front frame housing for the propelling mechanism thereof, a horizontal load supporting platform extending rearwardly from said housing, a pillar member rising from the platform, a boom support pivotally mounted thereon, a boom pivotally connected to the support adjacent its lower extremity, a frame structure extending above said truck frame housing and means mounted

10. In a crane, the combination of a rotatable support, a boom pivotally mounted thereon, a bar member pivotally connected to the boom, a tubular member pivotally connected to the support, and means associated with the tubular member whereby the bar member and the tubular member may be locked together and the boom maintained in an adjusted position.

In testimony whereof, I hereunto affix my signature.

CLYDE E. COCHRAN.
